Application filed December 18, 1885. Serial No. 186,090. Term of patent 3½ years.

To all whom it may concern:

Be it known that I, THOMAS J. STEARNS, of Boston, in the county of Suffolk and State of Massachusetts, have invented a certain new and original Design for Carpets, of which the following is a specification.

The nature of my design is fully shown in the accompanying photographic illustration.

The design is composed of the floral, foliage, to and vine ornamentation shown, the leading features of the design being the blossoms with varigated centers, the foliage, and the vines or stems having small pendants, as shown.

I do not claim the configuration shown in

I claim—

The design for a carpet, substantially as shown and described.

Intestimony whereof I have signed my name to this specification, in the presence of two subscribing witnesses, this 14th day of December, 1885.

THOMAS J. STEARNS.
